(57) **CLAIM**

The ornamental design for a remote control for a vertical digital projector, as shown and described.

DESCRIPTION

FIG. 1 is a front view of a remote control for a vertical digital projector showing our new design;

FIG. 2 is a side view of the remote control of FIG. 1;

FIG. 3 is another side view of the remote control of FIG. 1;

FIG. 4 is a rear view of the remote control of FIG. 1;

FIG. 5 is a top view of the remote control of FIG. 1;

FIG. 6 is a bottom view of the remote control of FIG. 1; and,

FIG. 7 is a reduced side view of the remote control of FIG. 3, attached to a vertical digital projector (which it controls) shown to illustrate environment only and forms no part of the claimed design.
